H. S. FREEMAN AND F. ZENKER.

ELECTRIC SWITCH.

APPLICATION FILED OCT. 29, 1917.

1,400,281.

Patented Dec. 13, 1921.

FIG. 1

FIG. 3

FIG. 2

Harry S. Freeman Inventors
and Frederick Zenker,
their Attorney.

Clifford E. Dunn

UNITED STATES PATENT OFFICE.

HARRY S. FREEMAN, OF DETROIT, AND FREDRICK ZENKER, OF HIGHLAND PARK, MICHIGAN, ASSIGNORS TO SQUARE D COMPANY, OF DETROIT, MICHIGAN, A CORPORATION OF MICHIGAN.

ELECTRIC SWITCH.

1,400,281.

Specification of Letters Patent. Patented Dec. 13, 1921.

Application filed October 29, 1917. Serial No. 198,918.

To all whom it may concern:

Be it known that we, HARRY S. FREEMAN, a citizen of the United States, and FREDRICK ZENKER, a subject of the Emperor of Germany, residents of Detroit, county of Wayne and State of Michigan, and of Highland Park, county of Wayne and State of Michigan, respectively, have invented certain new and useful Improvements in Electric Switches, of which the following is a specification.

This invention relates to electric switches and with regard to certain more specific features thereof to combined fuse-carrying and circuit-controlling switches.

In our co-pending application 198,256, filed October 24, 1917, we have shown one form of fuse-holding switch which may be readily assembled from parts, the majority of which are of standard construction. As such parts may be produced by the usual machinery, they are much cheaper than the special parts which have heretofore been used. In addition, such standard parts have a known performance. The type of switch which is exemplified by an embodiment there shown is very satisfactory where economical use of space is necessary.

An object of our invention is to improve a switch of the above type, in that we are able to dispense with nearly all the special parts of that switch. While our improved switch is a little longer than the one described in the prior application, it still shows a very economical use of space.

Another object of the invention resides in the construction and arrangement of certain of the contacts which makes for a high degree of accessibility and enables the operator to attach and detach the fuse from its contacts with ease and convenience.

Compactness and the reduction of parts to a minimum are other objects of the invention.

Further objects will be in part obvious and in part pointed out hereinafter.

While our invention may take form in many different embodiments, we will describe in detail one of these embodiments showing a construction having one convenient arrangement of parts and combination of elements for making up a switch. The scope of our invention is, however, to be limited solely by the claims and the prior state of the art.

In the accompanying drawing wherein is shown one of various possible embodiments of the invention,—

Figure 1 is a view in side elevation of a switch comprising the invention. 60

Fig. 2 is a sectional view taken on the line 2-2 of Fig. 1.

Fig. 3 is a sectional view taken on the line 3-3 of Fig. 1.

Referring now more particularly to the drawing, wherein similar reference characters refer to similar parts throughout the several views, there is indicated at 1 a base block of insulating material to which is attached the copper angle member 2. The attaching means comprises a screw 3 passed upwardly from the bottom of the base block through one arm of the angle member and through the tang of a terminal member 4, the terminal member and angle member being secured together and to the base by a nut 5. The upstanding arm 6 of the angle member 2 is apertured to receive a pivot stud 7 comprising a head 8 and a shank 9, a portion of the shank being threaded as indicated at 10 to receive a nut 11.

Secured to an insulating bridge element 15 by means of a screw 16 is a clip contact 17 having in the form shown a flat attaching portion 18 and depending walls 19 bowed inwardly as at 20 and continued in the form of spaced jaws 21 which straddle the upstanding wall 6 of the angle member 7 and which are apertured as at 22 to receive the shank of the pivot stud 7. Bearing 90 against the outer surfaces of these jaws 21 on either side are the compression disks or spring washers 23 which are given a suitable tension by manipulation of the nut 11 on the threaded portion 10 of the pivot bolt. 95 By this mechanism the clip contact 17 may be pivotally mounted on the upstanding arm 6 of the angle member 2 with sufficient tension to provide good electrical contacting engagement without any undesirable binding. 100

In addition to the clip contact 17 there are mounted on the bridge element 15, spaced apart clip contacts 30 and 31. The contact 30 electrically communicates with the contact 17 by means of a connector strip 32 secured to the contacts and to the bridge element by screws 16 and 34. The contact 31 is secured directly to the bridging element by a screw 35. All three contacts of the bridg- 110

ing element are in the form shown in longitudinal alinement and clips 30 and 31 are adapted to detachably receive a cartridge fuse 40 by means of its extending flattened 5 knife-blade terminals 41 and 42. The clip contacts 30 and 31 are similar in construction, each provided in the form shown with a flat comparatively wide attaching portion 43 from which there are depending side walls 10 44 bowed inwardly as at 45 and thence downwardly as at 46 to form substantially parallel compression jaws. At the joint where the inward bow 45 meets the downward extension 46 a small projection 47 is struck 15 inwardly to serve as a limiting stop for the fuse terminals when the latter are inserted between the spaced walls 46. In position to engage with the contact 31 when the bridge element 15 is pivotally moved toward the 20 base 1 there is mounted on the latter a clip contact 50 which comprises a flat attaching base 51, upstanding parallel walls 52 bent over as at 53 and downwardly as at 54, the downward extensions providing contact 25 jaws adapted to bear against the outer surfaces of the walls or jaws 46 of the clip contact 31.

When the parts are in their position as shown in full lines in Fig. 1 an electrical 30 circuit is established from the terminal 4 through the angle member 2, clip contacts 17, connector strip 32, clip contact 30, fuse terminal 41, through the fuse to its opposite terminal 42 and thence through the walls or jaws 35 46 of the clip contact 31, through the contact 50, through a connector strip 55 to a terminal 56. The clip contacts 30 and 31 being insulated from each other by the bridging element 15 and the contacts 2 and 50 being 40 insulated from each other by the base 1, the circuit between the latter contacts necessarily includes the fuse. If the fuse "blows" it is only necessary to manipulate the bridging element 15 by a handle 60 to separate 45 the contacts 31 and 50, whereupon the blown fuse may be quickly and conveniently removed and a new fuse attached in place thereof. Particular attention is directed to the simplicity and compactness of the present construction.

As many changes could be made in the above construction and as many apparently widely different embodiments of the invention could be made without departing from 55 the scope thereof, it is intended that all matter set forth in the foregoing description or shown in the accompanying drawings shall be interpreted as illustrative and not in a limiting sense.

What is claimed is:—

1. In an electric switch, the combination with a flat terminal fuse member, a base member and spaced contact members mounted thereon one of which comprises a U-shaped member, the outer ends of which are bent inwardly over and downwardly to form spaced double-wall resilient legs that are upstanding from the base, of a carrier comprising a pair of spaced contact members each having a pair of resilient jaw-members that are severally adapted to receive between said jaw-members in sliding engagement the flat terminal member, one of said carrier contact members with the interposed flat terminal member being received in sliding engagement in said U-shaped contact member mounted on said base. 60 70 75

2. In an electric switch, the combination with a base member and spaced contact members mounted thereon one of which comprises a U-shaped member, the outer ends of which are bent inwardly over and downwardly to form spaced double-wall resilient legs that are upstanding from the base and the other serving as a pivot member, of a carrier pivotally secured to said pivot member, a pair of spaced contact members secured to said carrier each having a pair of resilient jaw-members, and a fuse element 90 provided with flattened terminals that are received in sliding engagement in said carrier contact members, one of said carrier contact members with the interposed flat fuse terminal being adapted to engage in knife-blade fashion said U-shaped base contact member. 80 85 95

3. In an electric switch, the combination with an insulating base member and spaced contact members mounted thereon one of which comprises a U-shaped member, the outer ends of which are bent inwardly over and downwardly to form spaced double-wall resilient legs that are upstanding from the base and the other serving as a pivot member, of a carrier, spaced contact members secured to the under side of said carrier, one of said contact members being pivoted to said contact pivot members mounted on the base, and a fuse element having flat terminals slidably secured to said carrier contact members one of which, in combination with its interposed flat terminal of said fuse element, being received in sliding engagement in said U-shaped contact member 100 105 110 115 mounted on the base.
